UNITED STATES PATENT OFFICE

MAX J. SIEGEL, OF NEW YORK, N. Y., ASSIGNOR TO VINCENT W. CAHILL AND
B. ROBERT SWARTBURG, BOTH OF NEW YORK, N. Y.

REVOLVING WINDOW SASH

Application filed October 17, 1930. Serial No. 489,301.

This invention concerns window sashes and more particularly a window sash in which a window is rotatably mounted.

One of the objects of my invention is to provide in a sliding window sash, a rotatable window which is normally substantially invisibly fitted against said sash so that in respect to simplicity and security, and general practicability, my improved device has all the advantages of the ordinary sliding sash. But the incorporation of a revolving window in a slideable sash offers improved means for ventilation and, of course, the cleaning of the window is greatly facilitated, my improved construction allowing the window to be fully reversed in the sash, so that both sides of the window can be cleaned from the inside of a buiding.

Another object of my invention is to combine the mechanism, by means of which the revolving window is locked in the sash, with the fulcrum around which the window is adapted to rotate, thus simplifying the construction and facilitating maintenance and repair.

Another object of my invention is to concentrate the means which serve to lock a revolving window in a sash at the substantially centrally disposed fulcrum of said revolving window, so that the lock means, which extend along the whole length of the sash are centrally operated. Under these circumstances, the least exertion is required to operate the balanced locking means; only the operation of one simple, foolproof lever on each side of the window is required.

Another object of my invention is to adapt my improvement to modern sashes which are narrow and thin, thus leaving the greatest possible space of the window frame available for panes.

Additional objects of my invention are brought forth in the following description which is illustrated by the accompanying drawing, in which:—

Fig. 1 shows, in a parallel-perspective view, a window frame and a sash to which my revolving window is applied.

Fig. 2 shows a sectional, sectioned detail

front view of the fulcrum and the surrounding parts of the sash in the window.

Fig. 3 shows a corresponding horizontal cross section.

Fig. 4 shows a corresponding side view in 55 a combination of two vertical sections.

Similar numerals refer to similar parts throughout the several views.

In the view of Fig. 1, a staff head 11 and a removable inner staff 12 arise from the sill 60 13 of the window frame 10 upon the sides of said frame and form the stile runways 14 in which the sash 15 is slidably accommodated. The sash 15 comprises two U-shaped stiles 16, which are, substantially parallel 65 to each other, slidably accommodated in opposite runways 14, and the revolving window 18, which is rotatably supported by and between said stiles. The length of the stiles 16 corresponds substantially to the height of 70 the window 18. The lock handles 19 extend from the sides 20 of the revolving window near the fulcrum of said window and the sides are countersunk underneath the said handle, the respective openings 21 being of 75 such shape as to fully receive the handles 19 when they are swung down into a locked position; at the same time, openings 21 offer clearance spaces 22 at their lower ends, which allow the insertion of a finger for engaging 80 below the handles 19, when said handles are fully swung into and concealed in the sides 20 of the window.

The stiles 16 are provided with grooves 85 23 and the sides 20 of the window are provided with similar grooves 24 which register with the grooves 23 in the stiles when the window 18 is swung into a vertical position of alignment with the sash. To lock the window when it is in that position of alignment, the channels 25, which are completely accommodated by the grooves 24, as long as the window is unlocked, are slid into the grooves 23 in the stiles and engage thereupon in tongue fashion. The pane is retained in the revolving window 18 by the detachable moulding 27.

The fulcrum around which the revolving window 18 is adapted to swing in the sash 15, consists of a stud 28 which rotatably ex- 100

tends across the whole width of the stile 16 and which extends part-ways into a suitable bore 29 in the sides 20 of the window, in rotatable abutment against a collar 30. That 5 collar 30 is rotatable in the bore 29 and is thrustwise retained therein by a shoulder 31 at the end of the bore. The handle 19 forms part of the collar 30 and extends substantially tangentially therefrom. The collar 30 10 is provided with a tapped hole which is threadedly engaged by a screw 32. The screw 32 has a steep thread and it is fastened at one end by a flat head screw 33 upon the channel 25.

15 The stud 28 is provided with a slot 34 of a width clearing the channel 25 and of the grooves 23 and 24. The slots 34 in the studs are kept in alignment with the grooves 24 in the sides of the window by the channels 25 20 which are slidably disposed in said slots and in the whole length of the grooves 24 in the sides of the window. Since the channel 25 is in its furthest position to the right in the detail views of Figs. 2, 3 and 4, the stud 25 32 extends from the back of the collar 30, and the handle 19 is in its highest position, its top resting against the shoulder 35 at the upper end of the slot 21, which is substantially tangentially disposed in respect to 30 the bore 29. When the handle 19 is swung down into the opening 21, so that it fully disappears therein, the screw 32 is fed to the left by that operation, and the screw pushes the channel 25 partly out of the groove 24 35 into the groove 23 in the stiles, provided the revolving window is in its normal, vertical position. The screw is supported in the threaded opening in the collar 30 and in the hub 36, which laterally extends from said 40 collar, so that the screw and the channel fastened thereupon are predeterminedly retained by said parts at all times.

The handle 19 swings through a right or obtuse angle during its operation. The head 45 of screw 32, which is provided with a single or a multiple thread, is such that the channel 25 is shifted from its position in groove 24 into locking engagement with groove 23 of stile 16, when the screw is swung, by downward movement of handle 19, through said angle. The depth of groove 23 is such, as to accommodate the channel 25 in secure locking engagement.

The end of the stud 28 is provided with a 50 clearance opening 37, for the purpose of disassembling the revolving window from the sash. The sash 15 may be removed from the window frame after the inner staffs 12 have been unscrewed from the sides of the window frame. Then the screw 33 is taken off the 55 screw 32 by means of a screw driver inserted through the opening 37 in the end of the stud 28. The channel 25 can then be removed from the slot 34 and the groove 24. This 60 allows the withdrawal of the stud 28 from

the sash and from the revolving window so that the revolving window can now be taken out of the sash. The procedure is reversed when the parts of my improvements are to be assembled.

It will be seen that the openings between the sides of the revolving window and the stiles of the sash are fully closed, along their whole extent, by the channel 25, when the handle 19 is locked. This affords full protection against the weather, and the free ends of the channel 25 may be slightly flared outwardly so as to engage frictionally upon the sides of the grooves 24. The ease with which the locking handle 19 may be operated may thus be regulated. When the device is locked, the handle 19 disappears entirely in the opening 21 in the sides of the revolving window, so that there is no obstruction when another sash slides up and down in the window frame on top of my sash.

While I have shown and described my invention with some degree of particularity, it will be realized that other modifications and changes may be resorted to under special conditions. I therefore do not wish to be limited and restricted to the exact details shown and described, but reserve the right to make such changes and modifications as may fairly fall within the scope of the subject matter now being claimed.

Having shown and described my invention, what I claim is:—

1. In combination with a sash, stiles forming a frame, a window fitting into said frame, coaxially disposed studs extending from opposite sides of said frame into said window and rotatably supporting said window in said frame, and tongues in said window adapted to be slid in said studs into engagement with said frame.

2. In combination with a sash, stiles forming a frame, a window fitting into said frame, coaxially disposed studs extending through opposite sides of said frame into said window and rotatably supporting said window in said frame, and tongues in said window adapted to be slid in said studs into engagement with said frame.

3. In combination with a sash, stiles forming a frame, a window fitting into said frame, coaxially disposed studs extending through opposite sides of said frame into said window and rotatably supporting said window in said frame, tongues fitting through slots in said studs and into registerable grooves in said frame and said window, and means adapted to slide said tongues in parallelism from one of said grooves into a groove which is registerable with said former groove.

4. In combination with a sash, stiles forming a frame, a window fitting into said frame, coaxially disposed studs extending through opposite sides of said frame into said window and rotatably supporting said window in said

frame, tongues fitting through slots in said studs and into registerable grooves in said frame and said window and means centrally engaged upon said tongues, and adapted to 5 slide said tongues in parallelism from one of said grooves into a groove which is registerable with said former groove.

5. In combination with a sash, stiles forming a frame, a window fitting into said frame, 10 coaxially disposed studs extending through opposite sides of said frame into said window and rotatably supporting said window in said frame, tongues fitting through slots in said studs and into registerable grooves in said 15 frame and said window, a screw member laterally extending from one of said tongues in one of said studs, and a rotatable collar threadedly engaged upon said screw member, but laterally confined in respect to said stud, 20 so that rotation of said collar laterally shifts said tongues in said registerable grooves.

6. In combination with a sash, stiles forming a frame, a window fitting into said frame, 25 coaxially disposed studs extending through opposite sides of said frame into said window and rotatably supporting said window in said frame, tongues fitting through slots in said studs and into registerable grooves in said 30 frame and said window, a screw member laterally extending from one of said tongues in one of said studs, a rotatable collar threadedly engaged upon said screw member, but laterally confined in respect to said stud, and 35 a handle tangentially extending from said collar and out from said window and extending below the plane of the surface of said window when swung with said collar into a clearance opening in said windows.

7. In combination with a sash, stile forming a frame, a window fitting into said frame, 40 coaxially disposed studs extending from opposite sides of said frame into said window and rotatably supporting said window in said frame, collars with threaded openings axially 45 substantially parallel with said studs and rotatably seated in the sides of said window, handles forming part of said collars, extending from the face of said window through clearance openings therein and adapted to 50 swing said collars through predetermined angles between the parts of said window confront said openings, and screw members engaged in the threaded openings in said collars, completely accommodated in said window 55 when said handles are swung into one extreme position, and laterally protruding from said window and engaged upon said frame, when said handles are swung into the other extreme position and when said window is aligned in said frame.

8. In combination with a sash, stiles forming a frame, a window fitting into said frame, 60 coaxially disposed studs extending from opposite sides of said frame into said window and rotatably supporting said window in

said frame, collars with threaded openings coaxially disposed with said stud and rotatably seated in the sides of said window, handles forming part of said collars, extending from the face of said window through clearance openings therein and adapted to swing said collars through predetermined angles between the part of said window confronting said openings, and screw members engaged in the threaded openings in said collars, completely accommodated in said window when said handles are swung into one extreme position, and laterally protruding from said window and engaged upon said frame, when said handles are swung into the other extreme position and when said window is aligned in said frame. 70

9. In combination with a sash, stiles forming a frame, a window fitting into said frame, 75 coaxially disposed studs extending from opposite sides of said frame into said window and rotatably supporting said window in said frame, collars with threaded openings coaxially disposed with said studs and rotatably seated in the sides of said window, handles forming part of said collars, extending from the face of said window through clearance openings therein and adapted to swing said collars through predetermined angles between the part of said window confronting said openings, screw members engaged in the threaded openings in said collars and laterally reciprocated in respect to said window when said handles are swung back and forth, and tongues mounted upon the ends of said screw members, accommodated in grooves in the sides of said window and adapted to extend from said grooves into registering grooves in said stiles, when said handles are 80 85 90 95 100 105 110 115 120 125 130 aligned in said frame.

10. In combination with a sash, stiles forming a frame, a window fitting into said frame, 110 coaxially disposed studs extending from opposite sides of said frame into said window and rotatably supporting said window in said frame, collars with threaded openings coaxially disposed with said stud and rotatably seated in the sides of said window, handles forming part of said collar, extending from the face of said window through clearance openings therein and adapted to swing said collars through predetermined angles between the part of said window confronting said openings, and screw members engaged in the threaded openings in said collars and laterally reciprocated in respect to said window when said handles are swung back and forth, and channel-shaped tongues mounted upon the ends of said screw members, accommodated in grooves in the sides of said window and adapted to extend with their closed ends from said grooves into registering grooves in said stiles, when said handles are swung into one extreme angular position.

11. In combination with a frame and an 130

object mounted thereon, means rotatably connecting said frame with said object, and transversely slidable means extending through said connecting means and into said frame and said object, and adapted to be slid from one of the said last mentioned two parts into the other.

12. In combination with a frame and an object mounted thereon, means rotatably connecting said frame with said object, slidable means extending through said connecting means and into said frame and said object, and adapted to be slid from one of the said last mentioned two parts into the other, and means rightangularly extending from said slidable means and slidably accommodated in said connecting means.

13. In combination with a frame and an object mounted thereon, means rotatably connecting said frame with said object, slidable means extending through said connecting means and into said frame and said object, and adapted to be slid from one of the said last mentioned two parts into the other, and means rightangularly extending from said slidable means and axially slidably accommodated in said connecting means.

14. In combination with a frame and an object mounted thereon, means rotatably connecting said frame with said object, slidable means extending through said connecting means and into said frame and said object, and adapted to be slid from one of the said last mentioned two parts into the other, means rightangularly extending from said slidable means and slidably accommodated in said connecting means, and means moving said rightangularly extending means back and forth in said connecting means.

40 In testimony whereof I affix my signature.
MAX J. SIEGEL.
